UNITED STATES PATENT OFFICE.

THOMAS L. SMITH, OF MILWAUKEE, WISCONSIN.

ROCK-CRUSHER.

1,071,362.

Specification of Letters Patent. Patented Aug. 26, 1913.

Application filed August 12, 1910. Serial No. 576,842.

To all whom it may concern:

Be it known that I, THOMAS L. SMITH, a citizen of the United States, residing at Milwaukee, in the county of Milwaukee and 5 State of Wisconsin, have invented a new and useful Rock-Crusher, of which the following is a specification.

My invention relates to improvements in rock crushers and the objects of my improvement are to provide a relatively small machine, that can be built at a reasonable cost, and will retain the advantages of the 10 gyratory principle, also to provide an unobstructed feed opening in order that a larger piece may be crushed therein than in the present form of machines of similar 15 type, also to provide a ball and socket joint of ample surface to resist the heavy strains of crushing and to so place this spherical 20 bearing as to avoid all obstruction of the feed opening.

In the drawings which are a part of this specification, Figure 1 is a vertical section through the longitudinal center line of the machine. Fig. 2 is a plan view of the machine, Fig. 3 is an end view of the device 25 without the pulley, drawn to a smaller scale with half of the stationary crushing plate broken away, and Fig. 4 shows one of the 30 distance washers.

10 is the frame of the machine provided with the four feet, 11, through which the crusher is bolted down to its foundations. 12. Running in babbitt bearings, 14 in the 35 frame is the eccentric sleeve, 15. The outside of this sleeve is turned on the center line *a a* and the sleeve is bored on the center line *b b* these two lines intersecting in the point C. The crusher shaft or stem 16 is 40 free to turn in the eccentric bearings of the sleeve 15. The bevel gear 17 is secured to the rear end of the sleeve 15 and the cross shaft 18, supported in the journal boxes 19 carries the driving pulley 45 20 and the driving pinion 21. The gear- 25 ing is inclosed in the housing 22. The forward end of the shaft 16 carries the moving crusher head 23 which forms a partial spherical ball and socket joint with the front end 50 of the frame 10, the center of this spherical bearing being the point C. As the sleeve 15 is rotated the center line *b b* will gyrate around the center line *a, a*, and a wabbling motion is produced in the head 23.

55 24 and 25 are the hard steel or chilled iron plates between which the crushing is done.

These plates are embedded in lead, cast into the spaces between the plates and their seats. The flange 26 at the forward end of the frame contains a groove 27 in which the periphery of the head 23 makes a loose fit.

28 is a pipe connecting the groove 27 with a source of air, under slight pressure, so there is always a draft of air outward from the groove 27 to prevent dust and grit from settling in the groove and working into the 60 spherical bearing.

The stationary crusher plate 24 is carried in a separable part 29 of the frame, the two 65 parts being secured together by the bolts 30. To vary the distance between the crusher plates, either to change the size of the product or to compensate for wear, the bolts 30 can be loosened and washers 31 of the required 70 thickness put in place on each bolt. The sleeve 15 is positioned by the bevel gear 17 working against the end of the frame 10 and the plate 32 secured to the shaft 16 and forming a partial spherical joint with the 75 end of the sleeve 15, said joint having the point C for a center.

When the machine is running empty, the shaft 16 and head 23 will take up the rotation of the sleeve 15. When, however, the 80 head 23 meets with resistance to its wabbling due to the pressure of rock or ore between the crusher plates, the rotation of head 23 will cease although the wabbling will 85 continue. The plate 25 will be held up to 90 its work by the spherical bearing which will, therefore, take the strain of crushing. Although this strain is heavy, the relative movement of the ball and socket is very small, thus reducing the work of friction. 95 The work of gyrating the head is performed principally by the eccentric bearing of the shaft 16 near the driving shaft 18, and the long leverage from the center C to this bearing renders the movement very power- 100 ful.

By positioning the spherical bearing directly behind the movable crusher head the stress to which the crusher head is subjected is directly transferred to the bearing and as 105 the bearing is nearly equal in diameter to the crushing surface of the crusher head it lies in the direct line of stress for practically all portions of the crushing face so that the crushing head moves as a wedge between the 110 resisting material and the bearing. The center C of the spherical bearing being posi-

tioned at approximately the center of the space between the crushing faces gives to the movable crusher head for the greater portion of its effective crushing surface a maximum degree of localized direct approach and recession with relation to the stationary crushing head. This spherical bearing directly behind the movable crushing head gives to it the effect of being pivotally mounted at the point C midway between the crushing surfaces without the formation of an obstruction to the feed of material between the crushing faces and permits of the practically localized direct approach and recession of the greater portion of the crushing face without imposing stress to a material degree upon the driving mechanism. The approach and recession of the portions of the crushing surface of the movable crushing head with relation to the stationary crushing head is referred to as localized in contradistinction to the approach and recession which takes place with a crusher head of the oscillating type instead of the gyrating type of the present invention, for in the oscillating type of crusher head the movement is more or less a bodily movement instead of a localized movement in which the nearest point of approach of the crusher head travels around the axis of the movable crusher head.

What I claim as my invention and desire to secure by Letters Patent is:

1. A rock crusher comprising a frame bored longitudinally, a stationary plane crushing surface attached to said frame at an angle to said bore, an eccentrically bored sleeve rotatable in said bore and provided on its rear end with driving means, a shaft 40 rotatable in said eccentric sleeve and provided at its front end with a crushing head the crushing surface of which is in opposing proximity to said stationary crushing surface and is perpendicular to said shaft.
2. A rock crusher comprising a frame, a stationary crusher surface attached to said frame, a movable crusher head engaging the frame by means of a partial spherical bearing, an eccentrically bored sleeve rotatably mounted in the frame, a shaft attached to the crusher head substantially perpendicular to the crushing surface of the head and mounted in the bore of the sleeve, the prolonged center lines of the sleeve and shaft 55 meeting in the center of the spherical bearing, and means for rotating the eccentric sleeve.

3. A rock crusher comprising a frame, a crusher plate attached thereto, a movable crusher head on a ball and socket bearing, an eccentric sleeve in the frame, a shaft in said sleeve and carrying the crusher head said shaft being perpendicular to the crushing surface of said head, the center lines of the sleeve and shaft intersecting in the center of the ball and socket bearing, and driving means attached to said sleeve.

4. A crusher, comprising a stationary crushing member, a movable crushing member opposed thereto, a spherical bearing for the movable crushing member on the opposite side thereof from the stationary crushing member constituting a pivotal support for the movable crushing member with its pivotal center approximately midway between the crushing surfaces of the crushing members, and means for moving the movable crushing member on its bearing.

5. A crusher, comprising a stationary crushing member having a plane crushing surface, a movable crushing member with a plane crushing surface opposed to the stationary crushing member with its crushing surface at an angle to the crushing surface of the stationary crushing member to form a tapering passageway therebetween, a spherical bearing for the movable crushing member at the rear thereof forming a pivotal support for the movable crushing member with the pivotal center approximately midway between the crushing faces, and means for moving the movable crushing member on its bearing.

6. A crusher, comprising a frame, a stationary crushing member mounted thereon, a suitably driven sleeve journaled in the frame and provided with an eccentric bore, a stem journaled in the eccentric bore of the sleeve, a movable crusher head mounted on the stem and provided with a spherical bearing portion, a spherical bearing on the frame receiving the spherical bearing portion of the crusher head and forming therewith a pivotal support for the crusher head with the pivotal center approximately midway between the crusher head and the stationary crushing member.

In testimony of which, I have attached my hand, in the presence of two witnesses.

THOMAS L. SMITH.
